DESIGN FOR A LAMP

Herman L. Kraeft, Cleveland Heights, Ohio, assignor to The Murray-Ohio Manufacturing Company, Cleveland, Ohio

Application December 17, 1936, Serial No. 68,598

Term of patent 7 years

To all whom it may concern:

Be it known that I, Herman L. Kraeft, a citizen of the United States, residing at Cleveland Heights, in the county of Cuyahoga and State of Ohio, have invented a new, original, and ornamental Design for a Lamp, of which the following is a specification, reference being had to the accompanying drawing, forming a part thereof.

In the drawing, Fig. 1 is a plan view of a lamp showing my new design; Fig. 2 is a side elevation thereof; and Fig. 3 is a front elevation of the same. The lamp is adapted to be mounted on the handle-bar of a cycle of any type. The dominant features of the design are shown in full lines.

I claim:

The ornamental design for a lamp substantially as shown and described.

HERMAN L. KRAEFT.
